UNITED STATES PATENT OFFICE.

JOHN L. STICHT, OF THE UNITED STATES NAVY.

SHELL-FUSE.

No. 797,469.

Specification of Letters Patent.

Patented Aug. 15, 1905.

Application filed November 4, 1904. Serial No. 231,403.

To all whom it may concern:

Be it known that I, JOHN L. STICHT, a lieutenant in the United States Navy, residing at Hartford, in the county of Hartford and State of Connecticut, have invented certain new and useful Improvements in Shell-Fuses; and I do hereby declare the following to be a full, clear, and exact description of the invention, such as will enable others skilled in the art to which it appertains to make and use the same.

My invention relates to improvements in percussion-fuses; and it is intended to provide a fuse which shall be simple in construction, safe against accidents, and efficient in operation.

The fuse, as hereinafter described, is of that class of fuses in which the firing-plunger is normally separated from the cap by a shield and guard, which are both held in place in front of the firing-pin until the shell is spun up to a high rotary velocity caused by the rifling of the gun, and the shield and guard being released by the shock of firing the gun are caused to swing out and clear the firing-pin under the action of centrifugal force.

My invention relates especially to that class of fuses referred to in my pending application, Serial No. 214,403, filed June 27, 1904, entitled "Improvements in shell-fuses."

Reference is had to the accompanying drawings, in which the same parts are indicated by the same letters throughout the several views.

Figure 1 shows a section through a part of the base of the shell and through the axis of the fuse-stock, the igniting-charge in the fuse-stock being omitted. Fig. 2 represents a section across the housing for the plunger along the line 2-2 of Fig. 1, the parts being shown twice the scale of Fig. 1. Fig. 3 is a similar view to that shown in Fig. 2 and on the same scale except that the fuse is armed, and the section is taken along the line 3-3 of Fig. 1 and parts in front are shown in dotted lines. Fig. 4 shows a modification in which the shield is thrown out laterally under the action of centrifugal force, it being normally held in the safety position by two sets of springs; and Fig. 5 shows another modification in which the guard and the shield both lock by a pin on the plunger until released by the shock of the firing gun.

A represents a portion of the base of the shell into which the fuse-stock B is screwed

in the usual way. This fuse-stock is provided with a shoulder b in the interior thereof, with interior screw-threads b' extending through a considerable portion thereof, with a powder-chamber b² for the ignition charge, and with an annular recess b³ engaging the cap (not shown) for the ignition-chamber. It may also be provided with a lug b⁴ to engage the spring M, which will be hereinafter described.

The spring M may be held to plunger by a pin through the plunger holding it, or the spring may screw into screw-thread cut in plunger or may be secured thereto in any convenient way.

C represents the housing, which is screw-threaded through a large portion of its length, engaging the screw-threads b', this to secure firmer bearing, and the end of this housing abuts against the shoulder b when it is screwed home in the fuse-stock. This housing is chambered to receive the firing-plunger D, and in front of this chamber it is closed, as at C', and adapted to receive the percussion-cap or primer F, located in rear of the opening c⁰ in said housing C. The plunger D carries the firing-pin D', which may be secured to or made integral therewith; but for convenience of manufacture the firing-pin is preferably screwed into the plunger, as shown in Fig. 1. Said plunger also carries a locking-pin D², which projects from the front of said plunger somewhat farther than the point of the firing-pin, so that it may engage the swinging shield and lock the same in place, as will hereinafter be described. The housing C is slotted at one side, as at C⁰, (see Fig. 1,) to receive a centrifugal guard which is normally held in the closed position by means of a suitable spring or springs, but which is thrown out in the open position by the action of centrifugal force when the shell is spun up. By adjusting the compression of the spring the fuse may be so arranged that the shield will not be moved outward until the shell has attained a very high rotary velocity—say, for instance, three thousand revolutions per minute. Such a guard is shown at E in Figs. 1, 2, and 3, E' in Fig. 4, and E² in Fig. 5.

In Figs. 2 and 3 the guard E is held in place by springs L' and L² on a single bolt K, which bolt carries a nut k. In Fig. 4 there are two such bolts K and K' with corresponding springs. In Fig. 5 the centrifugal guard E² may be secured with either one or

two bolts and corresponding sets of springs, as shown in either Figs. 2 or 4. In any of these types the guard is provided with shoulders e e' , the former of which, e , abuts against the front face of the plunger D when the guard is in the closed position and acts as a positive stop to hold the firing-pin clear of the cap F. The shoulder e' bears against the bottom piece C' of the housing C and serves as a spacer for the guard to permit the swinging shield H to swing freely in front of said guard.

The shield H is pivoted on the pin h and is provided with a hole h' to engage the locking-pin D² with a recess h^2 to engage the point of the firing-pin and with a tip h^3 , which projects in front of the pin G, secured in the housing when the movable guard is in the closed position. The plunger C may be locked in place with a small brass wire or pin N, holding same into housing C, which wire is sheared when the gun is fired. In case this wire should become accidentally sheared, as from dropping the shell from a considerable height, I also provide a spring M, preferably attached to the plunger D, which normally presses the plunger forward, but which spring will yield to the inertia of the plunger after the pin N has been sheared by the shock of the discharge of the gun.

For convenience in centering this spring M a stud b^4 is preferably provided in the fuse-stock; but both the stud and the spring may be done away with and both the spring and the shear-pin may be done away with without rendering the fuse liable to premature explosion.

The devices shown in Figs. 1, 2, 3, and in Fig. 4 differ materially only in the single feature that two bolts or pins K and K', with corresponding springs L and L', are used in the device shown in Fig. 4, which would cause the guard E' to move out radially against the action of these springs, while in the device shown in Fig. 2 the guards will swing out as about a hinge.

The operation of the device will be precisely the same with the structures shown in Figs. 1 to 4. Thus when the gun is fired the first action would be to shear the pin N, causing the plunger to move back against the spring M, withdrawing the locking-pin D² from the swinging shield H. During the brief instant that this is being done the shell is being spun up in the gun, and centrifugal force throws the guard E or E' outward, permitting the tip h^3 of the swinging shield to clear the pin G and causing the shield to be thrown outward to the position shown in Fig. 3. This will remove all obstructions between the firing-pin and the percussion-cap F, and when the shell is suddenly arrested from any cause, as from striking the target, the plunger will fly forward and explode the cap.

The forward creeping of the plunger in flight, assisted by the reaction of the spring M, causes the firing-point to rest on or near the primer, but without sufficient force to explode the same; but on impact the fuse explodes.

In Fig. 5 a modification is shown in which the shield H² is curved and has its free end h^4 projecting beneath the guard E², and both shield and guard are locked in position by the locking-pin D², which projects into a recess c^2 in the housing C, as shown in Fig. 1.

When the gun is fired, the locking-pin D² will be withdrawn by the inertia of the plunger, as before described, and the shield and guard will be thrown outward by the spinning of the shell.

Thus it will be seen that in all the modifications shown the guard and shield constitute a double protection for the cap F, which cannot be fired unless both are swung outward, and this can only happen when the shell is spun up rapidly. In addition to these two obstructions to the forward path of the plunger I add the further protection of the locking-pin D², operating as described, and this locking-pin may be held in engagement either by a shear-pin N or spring M, or both, but even should both spring and shear-pin be omitted it will be seen that the guard and the shield would still protect the cap from the firing-pin.

As a still further protection the centrifugal guard may be held normally in place by weak springs, such as are shown in my application, Serial No. 214,403 aforesaid. These will not be necessary to the efficient and safe action of the fuse.

It will be seen that in case the primer-cap becomes unseated and free by shock of discharge, the shield being interposed between the primer-cap and the firing-point, prevents an indented blow sufficient to fire the primer.

The parts of the fuse are made extra heavy to withstand distortion and displacement of parts on shock of discharge or during severe dropping tests. The screw-thread is intentionally carried over most of the housing to prevent distortion of parts and to assist in giving rigidity to construction.

The parts of the fuse can be inspected, gaged, and assembled before being screwed into the fuse-body and will greatly facilitate inspection methods.

The shearing-wire is employed to take the weight of the plunger off the mainspring in case the shell is stood base end on, and the weight of the plunger rests on the spring, tending to make it set. This shearing-wire is intentionally made weak and will break during severe dropping tests.

It will be obvious that various modifications might be made in the herein-described apparatus which could be used without departing from the spirit of my invention.

Having thus described my invention, what I claim, and desire to secure by Letters Patent of the United States, is—

1. In a percussion-fuse, the combination with a fuse-stock, of a housing mounted in said stock and carrying the primer-cap, a plunger provided with a firing-pin and with a locking-pin, the plunger being mounted in said housing, a centrifugal guard connected to said housing and adapted to be thrown outward by centrifugal force, and a swinging shield pivoted to said guard and normally engaging said locking-pin, substantially as described.

2. In a percussion-fuse, the combination with a fuse-stock, of a housing mounted in said stock and carrying the primer-cap, a plunger provided with a firing-pin and with a locking-pin, the plunger being mounted in said housing, a centrifugal guard connected to said housing and adapted to be thrown outward by centrifugal force, and a swinging shield pivoted to said guard and normally engaging said locking-pin, with a spring tending to press said plunger forward in said housing, substantially as described.

3. In a percussion-fuse, the combination with a fuse-stock, of a housing mounted in said stock and carrying the primer-cap, a plunger provided with a firing-pin and with a locking-pin, the plunger being mounted in said housing, a centrifugal guard connected to said housing and adapted to be thrown outward by centrifugal force, and a swinging shield pivoted to said guard and normally engaging said locking-pin, with a shear-pin normally holding said plunger fast in said housing, substantially as described.

4. In a percussion-fuse, the combination with a fuse-stock, of a housing mounted in said stock and carrying the primer-cap, a plunger provided with a firing-pin and with a locking-pin, the plunger being mounted in said housing, a centrifugal guard connected to said housing and adapted to be thrown outward by centrifugal force, and a swinging shield pivoted to said guard and normally engaging said locking-pin, with a shear-pin normally holding said plunger fast in said housing, and a spring tending to press said plunger forward in said housing, substantially as described.

5. In a percussion-fuse, the combination with a fuse-stock, of a housing mounted in said stock and carrying the primer-cap, a plunger provided with a firing-pin and with a locking-pin, the plunger being mounted in said housing and both pins projecting therethrough, a centrifugal guard connected to said housing and adapted to be thrown outward by centrifugal force, and a swinging shield pivoted to said guard and engaging said locking-pin and interposed between said guard and housing and said cap, substantially as described.

6. In a percussion-fuse, the combination with a fuse-stock, of a housing mounted in said stock and carrying the primer-cap, a plunger provided with a firing-pin and with a locking-pin, the plunger being mounted in said housing and both pins projecting therethrough, a centrifugal guard connected to said housing and adapted to be thrown outward by centrifugal force, and a swinging shield pivoted to said guard and engaging said locking-pin and interposed between said guard and housing and said cap, with a spring tending to press said plunger forward in said housing, substantially as described.

7. In a percussion-fuse, the combination with a fuse-stock, of a housing mounted in said stock and carrying the primer-cap, a plunger provided with a firing-pin and with a locking-pin, the plunger being mounted in said housing and both pins projecting therethrough, a centrifugal guard connected to said housing and adapted to be thrown outward by centrifugal force, and a swinging shield pivoted to said guard and engaging said locking-pin and interposed between said guard and housing and said cap, with a spring tending to press said plunger forward in said housing and a shear-pin normally holding said plunger fast in said housing, substantially as described.

8. In a percussion-fuse, the combination with a fuse-stock, of a housing mounted in said stock and carrying the primer-cap, a plunger provided with a firing-pin and with a locking-pin, the plunger being mounted in said housing and both pins projecting therethrough, a centrifugal guard connected to said housing and adapted to be thrown outward by centrifugal force, and a swinging shield pivoted to said guard and engaging said locking-pin and interposed between said guard and housing and said cap, with a shear-pin normally holding said plunger fast in said housing, and a spring tending to press said plunger forward in said housing, substantially as described.

9. In a percussion-fuse, the combination with a fuse-stock, of a housing mounted in said stock and carrying the primer-cap, a plunger provided with a firing-pin and with a locking-pin, the plunger being mounted in said housing, a spring-compressed centrifugal guard connected to said housing and adapted to be thrown outward by centrifugal force against said spring action, and a swinging shield pivoted to said guard and normally engaging said locking-pin, substantially as described.

10. In a percussion-fuse, the combination with a fuse-stock, of a housing mounted in said stock and carrying the primer-cap, a plunger provided with a firing-pin and with a locking-pin, the plunger being mounted in said housing, a spring-compressed centrifugal guard connected to said housing and adapted

to be thrown outward by centrifugal force against said spring action, and a swinging shield pivoted to said guard and normally engaging said locking-pin, with a spring tending to press said plunger forward in said housing, substantially as described.

11. In a percussion-fuse, the combination with a fuse-stock, of a housing mounted in said stock and carrying the primer-cap, a plunger provided with a firing-pin and with a locking-pin, the plunger being mounted in said housing, a spring-compressed centrifugal guard connected to said housing and adapted to be thrown outward by centrifugal force against said spring action, and a swinging shield pivoted to said guard and normally engaging said locking-pin, with a shear-pin normally holding said plunger fast in said housing, substantially as described.

12. In a percussion-fuse, the combination with a fuse-stock, of a housing mounted in said stock and carrying the primer-cap, a plunger provided with a firing-pin and with a locking-pin, the plunger being mounted in said housing, a spring-compressed centrifugal guard connected to said housing and adapted to be thrown outward by centrifugal force against said spring action, and a swinging shield pivoted to said guard and normally engaging said locking-pin, with a shear-pin normally holding said plunger fast in said housing, and a spring tending to press said plunger forward in said housing, substantially as described.

13. In a percussion-fuse, the combination with a fuse-stock, of a housing mounted in said stock and carrying the primer-cap, a plunger provided with a firing-pin and with a locking-pin, the plunger being mounted in said housing and both pins projecting therethrough, a spring-compressed centrifugal guard connected to said housing and adapted to be thrown outward by centrifugal force against said spring action, and a swinging shield pivoted to said guard and engaging said locking-pin and interposed between said guard and housing and said cap, substantially as described.

14. In a percussion-fuse, the combination with a fuse-stock, of a housing mounted in said stock and carrying the primer-cap, a plunger provided with a firing-pin and with a locking-pin, the plunger being mounted in said housing and both pins projecting therethrough, a spring-compressed centrifugal guard connected to said housing and adapted to be thrown outward by centrifugal force against said spring action, and a swinging shield pivoted to said guard and engaging said locking-pin and interposed between said guard and housing and said cap, with a spring tending to press said plunger forward in said housing, substantially as described.

15. In a percussion-fuse, the combination with a fuse-stock, of a housing mounted in

said stock and carrying the primer-cap, a plunger provided with a firing-pin and with a locking-pin, the plunger being mounted in said housing and both pins projecting therethrough, a spring-compressed centrifugal guard connected to said housing and adapted to be thrown outward by centrifugal force against said spring action, and a swinging shield pivoted to said guard and engaging said locking-pin and interposed between said guard and housing and said cap, with a spring tending to press said plunger forward in said housing and a shear-pin normally holding said plunger fast in said housing, substantially as described.

16. In a percussion-fuse, the combination with a fuse-stock, of a housing mounted in said stock and carrying the primer-cap, a plunger provided with a firing-pin and with a locking-pin, the plunger being mounted in said housing and both pins projecting therethrough, a spring-compressed centrifugal guard connected to said housing and adapted to be thrown outward by centrifugal force against said spring action, and a swinging shield pivoted to said guard and engaging said locking-pin and interposed between said guard and housing and said cap, with a shear-pin normally holding said plunger fast in said housing, and a spring tending to press said plunger forward in said housing, substantially as described.

17. In a percussion-fuse, the combination with a fuse-stock, of a housing mounted in said stock and carrying the primer-cap, a plunger mounted in said housing and provided with a firing-pin and a locking-pin, and a centrifugal guard connected to said housing and engaging said locking-pin, substantially as described.

18. In a percussion-fuse, the combination with a fuse-stock, of a housing mounted in said stock and carrying the primer-cap, a plunger mounted in said housing and provided with a firing-pin and a locking-pin, and a spring-compressed centrifugal guard connected to said housing and engaging said locking-pin, substantially as described.

19. In a percussion-fuse, the combination with a fuse-stock, a housing mounted in said stock and carrying the primer-cap, a plunger provided with a firing-pin and a locking-pin mounted in said housing, a centrifugal guard engaging said locking-pin and being adapted to swing out when the shell is spinning, and a spring tending to press said plunger forward, substantially as described.

20. In a percussion-fuse, the combination with a fuse-stock, a housing mounted in said stock and carrying the primer-cap, a spring-compressed plunger provided with a firing-pin and a locking-pin mounted in said housing, a centrifugal guard engaging said locking-pin and being adapted to swing out when the shell is spinning, and a spring tending to

press said plunger forward, substantially as described.

21. In a percussion-fuse, the combination with a fuse-stock, a housing mounted in said stock and carrying the primer-cap, a plunger provided with a firing-pin and a locking-pin mounted in said housing, a centrifugal guard engaging said locking-pin and being adapted to swing out when the shell is spinning, a shear-

pin normally holding said plunger fast in said housing, and a spring tending to press said plunger forward, substantially as described.

In testimony whereof I affix my signature in presence of two witnesses.
